(57) **CLAIM**

The ornamental design for an electric bicycle, as shown and described.

DESCRIPTION

FIG. 1 is a top, rear and right side perspective view of an electric bicycle showing our new design;
FIG. 2 is a bottom, front and left side perspective view thereof;

FIG. 3 is a left side elevation view thereof;

FIG. 4 is a right side elevation view thereof;

FIG. 5 is a front elevation view thereof;

FIG. 6 is a rear elevation view thereof;

FIG. 7 is a top plan view thereof;

FIG. 8 is a bottom plan view thereof;

FIG. 9 is an enlarged view of the selected portion 9 in FIG. 1; and,

FIG. 10 is an enlarged view of the selected portion 10 in FIG. 2.

The broken lines shown in the drawings depict portions of the electric bicycle that form no part of the claimed design. The dot-dash lines in FIGS. 1-2 and 9-10 are provided for annotative purposes only to show the areas of enlargements. The dot-dash lines do not illustrate structures or subject matters and do not form part of the claimed design
